Primary Examiner — T Chase Nelson*Assistant Examiner* — Jonathan J. Han(74) Attorney, Agent, or Firm — Kirk A. Buhler; Buhler & Associates Patenting(57) CLAIM

The ornamental design for a fist hitch, as shown and described.

DESCRIPTION

FIG. 1 is a top perspective view of a fist hitch, showing my new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof;

FIG. 7 is a bottom plan view thereof; and,

FIG. 8 is a sectional view taken along lines 8-8 in FIG. 3. The broken lines depict environmental subject matter and form no part of the claimed design.

1 Claim, 8 Drawing Sheets(56)
